UNITED STATES PATENT OFFICE.

GEORGE H. FELT, OF NEW YORK, N. Y.

DESIGN FOR A MOSAIC PATTERN.

SPECIFICATION forming part of Design No. 23,059, dated February 13, 1894.

Application filed November 2, 1893. Serial No. 489,882. Term of patent 7 years.

To all whom it may concern:

Be it known that I, GEORGE H. FELT, a citizen of the United States, and a resident of New York city, in the county and State of New York, have invented a new and original 5 Design for a Mosaic Pattern, of which the following is a specification.

The drawing is a diagram of a mosaic pattern of my design in which there are two segregable features, one only being shown in part of the drawing and both are shown together in another part.

The leading feature of my design consists of 15 decagonal figures circumscribed with pentagonal figures in a composite system wherein these two forms of figures together with double truncated figures entirely cover the field in a new mosaic pattern.

Another feature of my design consists of a 20 system of pentagonal figures, irregular quadrilateral figures, and triangular figures inscribed within the decagonal figures of the said leading feature of the design for more elaborate ornamentation.

25 A represents the decagons. They are arranged at intervals apart in parallel lines *a*, and in other parallel lines *b*, crossing lines *a*, diagonally.

c represents the circumscribing pentagonal 30 figures, and *d*, the double truncated pentagonal figures, these being located between the decagons in the diagonal lines *b*. This constitutes the before mentioned essential part of my design.

35 In the other feature of my design, *f* represents a circle of pentagonal figures inscribed within one of the decagons *A*, of the said be-

fore mentioned essential part of my design, with triangular figures *g*, intermediate of the faces of the decagon and the inscribed pentagons.

h represents another circle of pentagons inscribed within the circle *f*, with exterior and interior irregular quadrilateral figures *i*, and *j* is a central pentagon with triangular figures *k* on each face in the angles between the figures *j*. It is to be understood that although this secondary feature of the design applies to all the decagonal figures *A* of the said essential part of the design, it is only 50 represented on one of the said figures in the drawing to illustrate the said essential feature independently, and to save repetition.

The elements of the design are to be variously colored as indicated by the shaded part 55 of the drawing.

I claim—

1. The design for a mosaic pattern consisting of the decagonal figures circumscribed with pentagonal figures and double truncated pentagonal figures as set forth.

2. The design for a mosaic pattern consisting of pentagonal figures, triangular figures and irregular quadrilateral figures inscribed within a decagon as set forth.

In testimony that I claim the foregoing as my invention I have signed my name, in presence of two witnesses, this 20th day of October, 1893.

GEO. H. FELT.

Witnesses:
